UNITED STATES PATENT OFFICE.

HENRY A. BRADLEY, OF NEW YORK, N. Y.

COAL-DUST FEEDER.

SPECIFICATION forming part of Letters Patent No. 295,145, dated March 18, 1884.

Application filed July 14, 1883. (No model.)

To all whom it may concern:

Be it known that I, HENRY A. BRADLEY, of New York, in the county and State of New York, have invented a new and Improved 5 Coal-Dust Feeder, of which the following is a specification.

In the drawings, Figure 1 represents a sectional side view of my improved coal-dust feeder. Figs. 2 and 3 are sectional views of 10 modifications of the same.

This invention has for its object the production of a device which will feed coal-dust in the presence of steam to a flame, and utilize the coal-dust in its original form, together 15 with the steam, for purposes of heating steam-boilers and the like.

The invention consists in the new combination of parts which constitute the feeder, as hereinafter more fully specified.

20 In Fig. 1 of the drawings, the letter A represents the coal-dust supply-pipe, which dips into the pile of dust at a suitable distance from the body of the feeder, and which contains a suitable cock, B, by which the size of 25 the channel through which the coal-dust passes to the feeder may be regulated. The end of the pipe A, which is nearest the feeder, is screwed or otherwise fastened in a cylindrical piece, C, which is surrounded by a 30 chamber, a, into which a steam-pipe, D, enters. The chamber a is of annular form. It may, at its lower part, be provided with a drip-pocket, b, from which the drippings may 35 escape through a short pipe, E, having a cock, d. The end of the pipe A within the cylindrical piece C is partly closed by a cap or plate, f, through which apertures g g extend into a chamber, h. This chamber h communicates also with the annular chamber a 40 by apertures i. The outer or face plate, j, of the chambers h has series of perforations l l. Each of these perforations l is by preference 45 in the range of a passage, g, and of a passage, i, as indicated by the dotted lines in Fig. 1.

45 The cap j is fastened to the head f by means of a bolt, m, or may be screwed upon the rim or wall n of the chamber h in suitable manner.

The operation of the feeder is as follows: 50 The pipe A, dipping into a supply of coal-dust, and the cock B being opened, and steam being admitted through the pipe D, the steam will rush into the chamber a, and thence

through the apertures i into the chamber h, whence it will escape through the apertures l. During this passage the steam will create suction in the apertures g and cause a supply of coal-dust to be drawn through the pipe A and through said apertures g into the chamber h, and thence out through the apertures l to the flame. The apertures g being aligned 55 with the apertures l, as shown, will cause the coal-dust to pass out in a straight line from the pipe A to and through the apertures l, and will prevent the retention of dust in the chamber h. It is desirable that the number 60 of apertures g should correspond with the number of apertures i and l, and that the said apertures be relatively arranged in the position indicated in the drawings.

Instead of passing the coal-dust through the 70 pipe A into the cylindrical piece C, and thence out through the head f, it may, as in Fig. 2, be carried by the pipe or pipes A through the chamber a to the partition p, which separates the chamber a from the chamber h, the said partition having in this case the apertures g. This leaves a central passage, o, in the cylindrical piece C, open at both ends, for supplying a charge of oxygen to the flame. Another modification, shown in Fig. 3, consists in conveying the coal-dust by the pipe or pipes A directly into the chamber h, thereby forming the inlet-openings g in the rim n of the chamber h.

I claim—

1. In a coal-dust feeder, the combination of 85 the pipe A, with the cylindrical piece C, chamber a, having apertures i, pipe D, head f, having apertures g, chamber h, cap j, having apertures l, all arranged with reference to each 90 other, substantially as herein shown and described.

2. The coal-dust feeder constructed with 95 chamber a, and steam-supply pipe D, leading thereto, and with the chamber h, having apertures g for receiving coal-dust, apertures i for receiving steam, and apertures l for the discharge of the mixed steam and coal-dust, substantially as herein shown and described.

HENRY A. BRADLEY.
